MARKER

John J. Jobe, Springfield, Ill.

Application July 13, 1936, Serial No. 90,450

1 Claim. (Cl. 101—328)

This invention relates to markers to facilitate the cutting of skins in the manufacture of fur garments.

In the manufacture of fur garments it is the practice to cut the edges of the skins, to be joined, to form a serrated or zig-zag edge and it is the object of the present invention to provide a device to mark the skins with a zig-zag line to guide the furrier in cutting the skins so that the zig-zag edges of the skins will be uniform, thus forming a more perfect fit when the skins are joined together.

A further object of the invention is to provide a device of the above-mentioned character which is simple and durable in construction, reliable and efficient in use, and inexpensive to manufacture.

Other objects and advantages of the invention will be apparent during the course of the following description.

In the accompanying drawing, forming a part of this specification, and in which like numerals are employed to designate like parts throughout the same,

25 Figure 1 is a perspective view of the device,
Figure 2 is a top plan view of the same, and
Figure 3 is a fragmentary plan view of a skin
showing the cutting line produced through the use
of my marker.

30 In the drawing, wherein for the purpose of illustration, I have shown a preferred embodiment
of my invention, the numeral 5 denotes a wooden
circular wheel, having a strip of rubber 6 applied
to its periphery and secured thereto by cement
35 and suitable fasteners. An upstanding rubber
rib 7 is formed integral with the outer surface of
the strip 6 and extends around the entire circum-
ference of the wheel in a zig-zag path, with
each angular portion extending the full width of
40 the wheel. A handle 8 is formed from a length
of pipe bent U-shaped to provide parallel side
arms 9, adapted to straddle the wheel, and have
their free ends flattened and slightly off-set in-
wardly, as at 10, for connection with the ends of
45 the axle 11 extending through the center of the
wheel 5.

A stick of chalk 12 is supported adjacent the periphery of the wheel 5, by a suitable holder consisting of spring members 13 carried by the side arms 9 of the handle. Each of the spring members 13 is formed of wire and extends longitudinally of the side arms 9 having one end fixedly attached to the side arms, as at 14, and their op-
50 posite ends slidably connected to the arms, as at

15. The fixed ends of the spring members are at-
tached to the side arms, at a point remote from
the wheel 5, by bending the wires around the arms
and passing the ends through transverse open-
ings 16 in the arms. The spring members are 5
arched upwardly from their fixed ends and at a
point adjacent the periphery of the wheel are bent
to form aligned loops 17, adapted to receive and
support the stick of chalk 12 transversely of the
wheel 5. 10

The loops 17 are connected by a transverse rod
17' which holds the loops in properly spaced re-
lation and which serves not only as a stop to
limit downward movement of the spring members
13 by engaging the rib 7 but also serves as a 15
handle by means of which the members 13 may
be raised for placing the chalk in position. The
ends of the spring members 13 beyond the loops
17 extend downwardly and slidably engage in the
vertical openings 18 in the side arms, the termi- 20
nals 19 being bent at right angles to limit the up-
ward movement of the chalk holder. The tension
of the spring members normally presses the stick
of chalk against the marking rib 7, so that upon
rotation of the wheel the chalk is applied to the 25
edge of the rib. When the wheel 5 is rolled across
a skin 20, a zig-zag line 21 is marked on the skin
which guides the furrier in cutting the skin. 30

In use, a stick of chalk 12 is inserted through
the loops 17 of the holder and is held firmly
against the rib 7 on the periphery of the wheel 5,
by the resiliency of the spring members 13. Upon
pushing the wheel 5, by means of the handle 8,
across the skin to be marked, the wheel is caused 35
to rotate and as the rib 7 passes the chalk 12 a
coating of chalk is applied to the edge of the rib.
The rib upon contacting with the skin, prints
thereon a zig-zag chalk line, thus marking the
skin so as to facilitate its cutting by the furrier. 40

It is to be understood that the form of my in-
vention herewith shown and described is to be
taken as a preferred example of the same and
that certain changes in the shape, size, and ar-
rangement of the parts may be made without de-
parting from the spirit of the invention or scope
of the subjoined claim. 45

What is claimed is:

A marking device comprising a rotatable wheel,
an axle for said wheel, a handle connected to said
axle and comprising substantially parallel mem-
bers each having a perforation therethrough, a
rubber strip applied to the periphery of said wheel
having an upstanding marking rib integral therewith,
a chalk holder carried by said handle con- 50
55

sisting of a pair of spring members disposed on opposite sides of said wheel, each member being formed of wire having one end affixed to said handle and its opposite end slidably mounted in 5 one of said perforations, the intermediate portion of the members being arched upwardly and bent

to form loops disposed in alignment, a bar connecting said loops at their tops and a stick of chalk mounted in the loops of said spring members and held thereby against the rib on the periphery of said wheel.

JOHN J. JOBE.
